US00D790758S

(12) **United States Design Patent** (10) **Patent No.:** **US D790,758 S**
(45) **Date of Patent:** **** Jun. 27, 2017**

(54) **LED OPTICAL LENS**

(71) Applicant: **SpeedTech Lights Inc.**, Buda, TX (US)

(72) Inventors: **Malik Deyaf**, Buda, TX (US); **Mostafa Abdallah**, Buda, TX (US)

(73) Assignee: **SpeedTech Lights, Inc.**, Buda, TX (US)

(**) Term: **15 Years**

(21) Appl. No.: **29/564,212**

(22) Filed: **May 11, 2016**

(51) LOC (10) Cl. **26-99**

(52) U.S. Cl.

USPC **D26/124**

(58) **Field of Classification Search**

(57) **CLAIM**

The ornamental design for a LED optical lens, as shown and described.

DESCRIPTION

FIG. 1 is a perspective view of a LED optical lens showing our new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof; and,

FIG. 8 is a perspective back view thereof.

The broken line portions in FIGS. 1-8 are included to show unclaimed subject matter only and form no part of the claimed design.

1 Claim, 6 Drawing Sheets
